VALVE OPERATING MECHANISM FOR
INTERNAL COMBUSTION ENGINESStanley Herbert Attwood, Wolverhampton, Eng-
land, assignor to Simms Motor Units Limited,

In Great Britain January 18, 1932

17 Claims. (Cl. 123—90)

This invention is for improvements relating to valve operating mechanism for internal combustion engines, and more particularly to valve operating mechanism for the fuel injection valve and inlet and exhaust valves of "live rail" Diesel or compression ignition engines. The expression "live rail" is employed to define that type of compression ignition engine in which fuel is maintained at relatively high pressure, (for example 3 to 5 tons per square inch), and admission of fuel to the engine cylinders is effected through an injection nozzle controlled by a fuel valve.

The invention has for some of its objects to provide valve operating mechanism in which the period of opening of a valve, especially a fuel injection valve, may be effected during a much smaller angle of rotation of the crank shaft of the engine than has heretofore been found possible; to provide a mechanism for fuel injection valves which enables the period of opening of the valve to be varied without effecting any alteration in the timing of the valve and vice versa; and to provide an automatic control which prevents the fuel injection valve from being maintained open during each cycle of operation of the engine for a period which would cause too great a quantity of fuel to be injected into the engine cylinder.

According to this invention there is provided a valve operating mechanism which comprises a pair of oscillatory cams, the actuation of both of which is necessary to operate the valve and therein one cam initiates and the other terminates the said operation.

Further, according to this invention there is provided an operating mechanism for a fuel injection valve of a "live rail" compression ignition engine which comprises a cam mechanism operable to actuate the valve and means operable to vary the timing of the instant of opening of the valve effected by said cam mechanism in a cycle of operation of the engine whilst the period of opening of the valve is maintained unaffected by said variations.

Again, according to this invention there is provided an operating mechanism for a fuel injection valve of a "live rail" compression ignition engine, which comprises means arranged to be operatively controlled by an accelerator pedal, or like member, for varying the period of opening of the valve and means operable automatically to vary the maximum period of opening which may be effected by the pedal or the like in accordance with the engine speed, for the purpose described.

The invention also consists in a valve operating mechanism which comprises an oscillatory cam arranged to open a valve in such a manner that the fully open position of the valve coincides with

the termination of a movement of the cam in one direction during an oscillation thereof.

In order that the invention may be fully understood, reference is directed to the accompanying drawings, in which:—

Figure 1 illustrates in vertical section the cylinder head of an internal combustion engine provided with a valve mechanism constructed in accordance with this invention;

Figure 2 is a plan of Figure 1 with an upper cover removed;

Figure 3 is a section of a detail on the line 3—3 of Figure 1;

Figure 4 is a vertical section of a portion of the engine illustrated in Figures 1 and 2 corresponding to a section on the line 4—4 of Figure 2;

Figure 5 is an end elevation of an engine embodying the valve mechanism illustrated in Figures 1 to 4 illustrating certain controls herein- after described;

Figure 6 is a view at right angles to Figure 5;

Figure 7 is a plan of Figure 6;

Figure 8 illustrates a detail of a slow running control for the engine illustrated in Figures 1 to 7;

Figure 9 is a view similar to Figure 5, but illustrating a modification of the invention;

Figure 10 is a section on the line 10—10 of Figure 9;

Figure 11 illustrates a detail of Figure 10, but with parts shown in different positions;

Figure 12 is a diagram illustrating the relationship of certain parts illustrated in Figures 9 to 11 hereinafter described;

Figures 13 to 16 are diagrams illustrating respectively different positions of the cams for the fuel valve of the engine illustrated in Figures 1 to 4 during a cycle of operation of the engine as hereinafter described, and

Figure 17 is a diagram showing the range of adjustment which may be obtained for the fuel valve both in respect of timing and period of opening as hereinafter described.

Referring to the drawings, the head 1 of one cylinder of a Diesel or compression ignition engine is illustrated which is provided with air inlet valves 2 and exhaust valves 3. Centrally at the cylinder head a fuel valve 4 is provided which in the example shown is constructed in accordance with British Patent application No. 1429 of 1932. At the upper end of the fuel valve stem a double-armed rocker 5 is pivotally mounted about a horizontal axis disposed transverse to the rocker and is provided at each of its ends with a downwardly directed curved shoe 6, which is concentrically arranged with respect to the axis of one of a pair of oscillatory shafts 7, 8. The shafts 7, 8 extend along the top of the engine over all the cylinders thereof arranged in line and are ro-

5

30

35

40

60

tatably mounted in a series of bearings, two of which are indicated at 9 in Figure 2. Hereinafter the shaft 7 will be referred to as the "period" shaft and the shaft 8 as the "time" shaft. The 5 shafts 7, 8 are coupled together at one end by a pair of helical gears 10, 11 and the gear 10 on the period shaft is slidably axially thereof in a manner hereinafter described to effect relative rotation between the two shafts; the gear 10 is 10 shown in its normal position in Figure 7 and is slidable in the direction of the arrow *a* to effect rotation of the shaft 7 in a clockwise direction, Figure 1, by virtue of the helical form of the gear teeth and the relative fixity of the gear 11 in the 15 axial and rotational directions; this direction of rotation of the shaft 7 has been generally indicated in the drawings by arrows *b*.

Each fuel valve is arranged to be operated by a pair of oscillatory cams 12, 13 mounted 20 respectively upon the shafts 7, 8 and the active surface of each cam is constituted by a curved surface arranged concentrically with respect to the axis of the respective shaft 7 or 8 which forms the axis of oscillation of the cam. Each cam is arranged to act upon the respective shoe 6 to lift the adjacent end of the rocker 5 through the medium of a relatively small roller 14 which is carried in a slot, formed in an annular lateral extension 15 of a collar 16 keyed to the respective 25 shaft 7 or 8. It will be seen more particularly from Figure 3 that the extension 15 surrounds the respective cam 12 or 13. The point during the oscillation of either of the cams 12 or 13, at which the cam is effective to actuate the rocker 30 5, depends upon the position of the respective roller 14 longitudinally of the curved surface of the shoe 6 associated therewith, and this position of the roller may be varied by a partial rotation of the respective shaft 7 or 8 which carries the 35 collar 16 and the roller 14 therewith. Whatever the operative position of the rollers 14 may be relatively to the respective shoes 6, the thrust of the cams on the shoes will always be radial and clearances between the said cams, rollers and 40 shoes will remain unaltered.

Each of the cams 12, 13 is formed integrally with one of a pair of eccentrics 17, 18, each coupled by a strap 19 and a connecting rod 20 to the strap 21 of one of a pair of eccentrics 22, 23 provided respectively upon rotatable shafts 24, 25.

The shafts 24, 25 are arranged to be rotated at half the crank shaft speed of the engine by gearing generally indicated at 25a, Figure 5, in 55 opposite directions as indicated by the arrows in Figure 4. The eccentric 22 is 52° out of effective phase with the eccentric 23, whilst the eccentric 17 is 42° out of effective phase with the eccentric 18. The relative angular disposition of the eccentrics 22, 23, 17 and 18 will be more clearly appreciated from the following particulars given with reference to the position of the cams 12 and 13 as shown in Figures 1, 4 and 13 in which the injection valve 4 is in the open position with the 60 piston at its top dead centre on the compression stroke. In this position of the various parts the peak radial line (Figure 13) of the eccentric 22 is advanced by an angle of 26° with reference to a radial line drawn from the axis of the shaft 24 at right angles to a line through the said axis and the axis of the shaft 7 while the eccentric 23 is retarded by an angle of 26° from a similar 70 radial line drawn at right angles to a line through the axes of the shafts 25 and 8. The peak radial line of the eccentric 17 is advanced by an angle of 75

21° with reference to a radial line through the axis of the shaft 7 disposed at right angles to the line extending through the axes of the said shaft 7 and the shaft 24, while the radial peak line of the eccentric 18 is retarded by an angle 5 of 21° from a similar radial line from the axis of the shaft 8 which is disposed at right angles to the line through the axes of the shafts 8 and 25. These particular angular displacements between the four eccentrics ensure the phase displacement between the cams 12 and 13 which causes the cam 12 to lead the cam 13 to a sufficient extent that during the inward movements of the cams towards one another the cam 12 will reach its inner reversing point and again return 10 to its roller 14 at a moment when a sufficient distance is still present between the cam 13 and its roller 14 to ensure that the cam 12 will completely pass its roller 14 before the cam 13 reaches its roller. From this explanation it will be clear 20 that the oscillatory motions of the cams 12 and 13 can be readily produced by any convenient pair of mechanisms for converting rotary motion of the engine crank shaft into reciprocatory motion, such mechanisms being known in many forms 25 and the eccentric mechanisms disclosed in the accompanying drawings being preferred as giving a very smooth and silent action. Whatever form of mechanism be used for oscillating the cams 12 and 13 the essential point is that one of the 30 cams, in the example the cam 12, shall lead the other cam, in the example the cam 13, by a sufficient amount to ensure that when the cams have passed their rollers in periods which overlap as the cams move in one direction, one of the 35 cams will reverse and reach its roller in the return motion while a sufficient distance still remains between the second cam and its roller, due to the lag of the second cam which ensures that by the time the second cam reaches its 40 roller the first cam will have passed its roller.

Thus the eccentrics 22, 23 as they rotate with the shafts 24, 25 effect oscillatory motion of the cams 12 and 13, and the phasing of the cams above referred to ensures that the movement of 45 the active surfaces of the cams towards one another in Figure 1 as indicated by the arrows *c*, *d*, ensures that the periods during which they pass their respective rollers 14 overlap one another in such a manner that they both act upon 50 the rocker together although the timing when each cam begins and ceases to act and the period during which they are both active, determined by the amount of overlap above referred to, may be varied as hereinafter described. During the 55 return movement of the cams away from one another in Figure 1 the cams pass their respective rollers 14 out of phase with one another in the manner above described, so that only one cam operates upon the rocker at a time, and the arrangement is such that the valve 4 is only open when both the cams 12, 13 raise the rocker 5. In one practical example, the cams 12, 13 are arranged jointly to effect a raising of the valve 4 from its seat by .015 inches.

It will thus be appreciated that with the arrangement described the valve 4 is not raised from its seat during the return movement of the cams 12, 13 in the opposite directions to the arrows *c*, *d*, Figure 1, the rocker 5 being merely 70 rocked idly about its pivot as each of the cams 12, 13 acts separately thereon.

The cams 12, 13 are also formed integrally with cams 26, 27, Figures 2 and 4, of which the cam 26 associated with the cam 12 is arranged to 75

operate the inlet valve 2 through the medium of a rocker 28, whilst the cam 21 associated with the cam 13 is arranged to operate the exhaust valve 3 through the medium of a rocker 29. With the arrangement illustrated the end of an oscillatory movement of both the cams 26, 27 is arranged to coincide with the mid-point of opening of the respective inlet or exhaust valves and each of the cams 26 or 27 is arranged to produce the maximum lift of the respective valve at this point. In the drawings each cylinder is shown as being provided with duplicate inlet and exhaust valves, each pair being operated together through the medium of the rockers 28, 29. The cams 26, 27 need not be formed integrally with the respective cams 12, 13 but may be formed separately and operatively connected in driving relationship with the latter cams. If desired, the cams 26, 27 may be driven by mechanism other than that which drives the cams 12, 13. Also the oscillatory motion of the cams 12, 13 and 26, 27 may be derived from cams in lieu of eccentrics such as 22, 23.

In the operation of the fuel valve by the cams 12, 13 the cam 12 first comes into operative association with its roller 14 and shoe 6 so that as soon as the cam 13 moves into the operative position to lift its roller 14 and shoe 6 the valve 4 is opened, and the point at which the cam 13 operates upon its roller 14 controls the timing of the valve 4, and, therefore, the timing of the ignition for the engine cylinder of the said valve. Thus, movement of the roller 14 in one direction or the other about the axis of the timing shaft 8 controls the said timing for the respective engine cylinder.

After the cam 13 has moved into the operative position to raise the valve 4 the period during which the valve remains open depends upon overlap of the cams 12 and 13 as they pass their rollers 14 together and this is determined in the example illustrated by the length of the active surface of the cam 12 which is still required to travel past its roller 14 before the adjacent end of the rocker 5 is allowed to fall and effect the closing of the valve 4 by the return spring 4a. Thus, the longest period of opening of the valve 4 is obtained when the cam 12 has only just moved into the operative position as the cam 13 also moves into the operative position whilst the shortest period is produced when the cam 12 moves out of the operative position almost immediately after the cam 13 has moved into the operative position to open the valve. The period during which the valve 4 remains open is, therefore, arranged to be controlled by moving the roller 14 associated with the cam 12 about the axis of the period shaft 7 in one direction or the other in a manner hereinafter described.

It will also be appreciated from the above description that when an alteration in the timing of the valve 4 by means of a movement of the roller 14 associated with the cam 13 is effected, it will also be necessary to effect a similar movement of the roller 14 associated with the cam 12 in order that the period of opening of the valve 4 may not be altered by an adjustment in the timing, and this is ensured by the coupling of the shafts 7 and 8 together by the helical gears 10, 11.

The relative positions of the cams 12, 13 during a cycle of operation of the engine are clearly illustrated in Figures 13 to 16 which show the manner in which the phasing of the said cams prevents them from opening the fuel valve during their return movements.

Figure 13 shows the cams 12, 13 in a position

similar to those illustrated in Figure 1, in which both cams are acting upon the rocker 5 and the fuel valve 4 is raised from its seat so that injection of fuel into the engine cylinder is being effected; the cams 12, 13 are shown at a point 5 during their movement in the direction of the arrows c, d. In Figure 14 the cam 12 is in its innermost or extreme clockwise position, so that the fuel valve 4 is closed whilst the cam 13 has not yet reached its innermost or extreme anti-clockwise position. In Figure 15 the cam 12 is in a position during its return or anti-clockwise movement, in which it is about to lift the adjacent end of the rocker 5, but the cam 13 has only reached its innermost or extreme anti-clockwise 10 position and is clear of its roller 14 so that the valve 4 remains closed whilst the cam 12 passes its roller 14; during this portion of the movement the cam 27 (not shown in Figure 15) is operating to open the exhaust valve which in the 15 position of the parts illustrated is in the mid-point of its opening period. In Figure 16 the cam 12 is in its outermost or extreme anti-clockwise position whilst the cam 13 is in a position during its outward or clockwise movement in 20 which it has just passed its roller 14 out of phase with the cam 12, so that the fuel valve 4 remains closed; this position of the cam 12 corresponds to the mid-point of the opening period of the inlet valve which is effected by the cam 26 (not 25 shown in Figure 16). It is to be noted that the cams 12, 13 are arranged to act upon the rocker 5 during the more rapid portion of their oscillatory movements and thus enable the accurate control of the fuel valve to be most readily obtained. 30

The cams 26, 27 on the other hand, are brought into effective operation to control the inlet and exhaust valves at the end of an oscillatory movement of the said cams which are then moving relatively slowly thus ensuring a minimum wear 35 on the cams and rollers.

Before proceeding to describe the various mechanisms which are employed to move the roller 14 about the axes of the shafts 7 and 8 for the purpose of altering the timing and period of opening of the fuel valve 4 reference is directed to Figure 17, and the following table which shows the different positions which the rollers 14 occupy relatively to one another for various periods of opening of the valve 4 with different timings. 40

In Figure 17 the cams 12, 13 are shown in positions corresponding to those in which the fuel valve is about to be opened at top dead centre of the compression stroke and for a maximum possible period when the respective rollers 14 are 45 in the positions A¹ and A. Each of the successive alternative positions for different time and period represent a movement of the crank shaft of the engine through an angle of 20°. 50

Time of opening		Time of opening		Time of opening	
Top dead centre		20 degrees before top dead centre		40 degrees before top dead centre	
Roller positions	Period	Roller positions	Period	Roller positions	Period
A A'	80°	B B'	80°	C C'	80°
A B'	60°	B C'	60°	C D'	60°
A C'	40°	B D'	40°	C E'	40°
A D'	20°	B E'	20°	C F'	20°
A E'	0°	B F'	0°	C G'	0°

With the construction of cam mechanism for the fuel valve as above described the period of 75

opening of the valve may be effected efficiently within an angular range of the engine crank shaft from a maximum of 80° to a minimum of 3° , giving a minimum period which is much 5 smaller than anything previously attained which has usually been from 15° to 20° of the engine crank shaft. The maximum period may obviously be increased by suitable increase in the 10 length of the active surface of the period cam 12 and time cam 13 to provide the necessary period of overlap of the cams.

In Figures 5, 6 and 7 an arrangement is illustrated in which the control of the time of opening of the valve 4 is effected by a governor of 15 known construction generally indicated at 30, and which is operatively connected to the timing shaft 8 by a link 31, double-armed lever 32, 33, link 34 and an arm 35 carried by the end of the shaft 8. As the speed of the engine rises the 20 governor operates automatically to rotate the shaft 8 in the direction of the arrow e, Figure 5, and thus the roller 14 of the timing cam 13 is moved in a clockwise direction in Figure 1, so that it is met by the leading edge of the cam 13 25 during its operative movement earlier in the cycle of operation of the engine and thus advances the time of opening of the fuel valve 4. This adjustment also effects the necessary counter clockwise adjustment of the roller 14 for the cam 12 30 through the medium of the gears 10, 11 as hereinbefore described so that the period of opening of the valve remains unaltered. Alternatively, the advance in timing of the opening of the 35 valve 4 may be effected by a manual control operatively connected to the time shaft 8 to enable the said shaft to be rotated in either direction.

The period during which the valve 4 is maintained open is controlled through the medium of 40 a lever 36 which is carried by a pivotally mounted spindle 37 and is arranged to be operatively connected to an accelerator pedal, or other similar control for the internal combustion engine. The spindle 37 has a toothed sector 38 keyed thereto 45 which is arranged in mesh with a series of annular rack teeth 39 formed upon an extension of the helical gear 10. Oscillatory movements of the lever 36 thus effect reciprocatory movements of the gear 10, whilst the annular form of the teeth 39 permits rotation of the gear 10 and rack 39 50 relatively to the sector 38, both during individual adjustment of the gear 10 as it moves axially to control the period of opening of the fuel valve by a clockwise rotational movement of the said gear 10, Figure 5, relatively to the gear 11, and as it is rotated with the shaft 8 and gear 11 during an 55 adjustment of the timing of the fuel valve.

To enable the slow running position of the period shaft 8 to be varied, the lever 36, Figure 8, 60 is arranged to be limited in its extreme slow-running position by a cam 36a provided upon a pivoted arm 36b which, in the case of the engine of a road vehicle, may be adjustable from a control situated on the dash board of the vehicle.

The amount of fuel injected into an engine cylinder operating upon the "live rail" principle 65 depends solely upon the pressure of the fuel in the supply conduit and the period during which the injection valve is open, which latter is dependent not only upon the setting of the roller 14 for the period cam 12 but upon the speed at 70 which the engine is running, and therefore the operation of the accelerator pedal or other control for the period of opening of the fuel valve to give the normal maximum period of fuel injection.

tion whilst the engine is running at slow speeds is undesirable, because this clearly results in an injection of too great a quantity of fuel. To avoid this undesirable feature a construction of control mechanism is illustrated in Figures 9 to 12 in which a governor is employed to control the extent to which the period of opening of the fuel injection valves may be increased by the accelerator pedal or other control for any particular engine speed. The principle of this arrangement 10 is such that during slow running of the engine the governor operates to reduce the amount of axial movement of the helical gear 10 for any given movement of the accelerator pedal or similar control. With the exception of this interconnection between the governor and the period control which is hereinafter described, the construction shown in Figures 9 to 11 is similar to that shown in Figures 5 to 7, time shaft 8 being arranged under the control of the governor 30 20 and the accelerator control operatively connected to the gear 10 of the period shaft 7. The various parts of the mechanism illustrated in Figures 9 to 12 have been indicated by the same reference numbers as the corresponding parts in Figures 5 25 to 7 where this is possible.

Referring to Figures 9 to 12 the spindle 37 of the accelerator lever 36 has an arm 40 keyed thereto which is connected by a link 41 to one end of a rack 42 which is slidably mounted in a hollow 30 arm 43 which forms an extension of the toothed sector 38 which is operatively connected to the annular rack teeth 39 hereinbefore described. When the rack 42 is in a position in which the link 41 is located in the position illustrated in 35 Figure 10, oscillatory movements of the spindle 37 by means of the lever 36 produce minimum angular movements of the arm 43 and sector 38, whilst when the rack 42 and link 41 are in the 40 positions indicated in Figure 11 such oscillatory movements of the spindle 37 produce maximum angular movements of the sector 38.

The arbour 44 of the sector 38 is provided with a hollow bore 45 into which the end of a rack 46 is arranged to extend. The rack 46 is slidably 45 mounted in a guide 47 mounted upon the engine frame, and the teeth of the rack are arranged to mesh with the teeth of the rack 42, the teeth of both racks being disposed at an angle of 45° to the axes of the respective racks in the manner 50 illustrated diagrammatically in Figure 12, so that movement of the rack 46 in the direction of the arrow f produces a movement of the rack 42 in an outward direction indicated by the arrow g in Figure 10. Normally, the racks 42 and 46 are in 55 the positions illustrated in Figures 9, 10 and 12.

The rack 46 is provided at its outer end with a series of annular rack teeth 48 arranged in mesh with a toothed sector 49 keyed to the time shaft 8. Thus, with the construction described, as the 60 engine gains speed and the governor 30 operates to advance the timing of the point of opening of the fuel valve by clockwise rotation of the time shaft 8 the toothed sector 49 moves the rack 46 in the direction of the arrow f, whereby the rack 65 42 is moved in the direction of the arrow g and the link 41 therewith resulting in a progressively increased angular movement of the sector 38 relatively to the angular movements of the lever 36 with increase of engine speed as above described. 70

The invention thus provides a valve operating mechanism for an internal combustion engine in which the opening period of a valve may be effected during an angle of rotation of the crank shaft of the engine which is much smaller than has 75

herefore been possible, and the mechanism is particularly free from variations in the clearances between the different operative members due either to strain or wear in the members themselves, variations in relative setting, or adjustment of the different members, or due to expansion or contraction of the parts of the mechanism with fluctuations in temperature owing to the relatively close assembly and concentric arrangement of the operative elements. Moreover, any slight errors in manufacture of the valve operating mechanism may readily be compensated when assembling the various parts; the collars 16 may, for example, be relatively adjusted around the shafts 7 and 8 before finally being keyed thereto, so as to compensate any slight discrepancies between the various cams 12 and 13 and their settings as determined by their operative connections to the eccentrics 22, 23. Also, when the invention is applied to the operation of a fuel injection valve for a Diesel engine the timing of the opening of the valve may be varied without causing any alteration in the period of opening of the valve, alterations in timing being automatically compensated in the period control so that the period is maintained constant for any particular setting of the timing control. In addition, the invention provides an automatic control which prevents the injection of too great a quantity of fuel when the engine is running at relatively slow speeds.

It is to be understood that the invention may also be applied to the valve mechanism of two-stroke cycle compression-ignition engines as well as to four-stroke cycle engines as above described, suitable alterations being made in the speed of operation of the cams in order to synchronize their action with the cycle of operation of the engine.

What I claim and desire to secure by Letters Patent of the United States is:—

1. In a valve actuating mechanism, a pair of oscillatory cams, a follower for each of said cams, a valve actuating member operable to be effectively actuated by said cams and followers only when both said followers are actuated together by said cams, a driving element adapted to be continuously rotated, and a pair of mechanisms each adapted to convert rotary motion into reciprocatory motion and connected on the one hand in driven relationship to said driving element with a phase displacement with respect to one another and on the other hand to one of said cams to oscillate the same through predetermined phase displaced angles determined by the phase displacement of said mechanisms, said followers being so positioned in the paths of oscillatory movement of the respective cams that the periods of actuation of the followers by the cams overlap during movement of the cams in one direction of their respective oscillations and follow in succession without overlap during movement of the cams in the other respective directions due to the phase displacement between the cams.

2. In a valve actuating mechanism, a pair of oscillatory cams, a follower for each of said cams, a valve actuating member operable to be effectively actuated by said cams and followers only when both said followers are actuated together by said cams, a pair of crank devices coupled together with a predetermined phase displacement relatively to one another and adapted to be uniformly rotated, mechanisms operable to convert the rotary motion of each of said crank devices separately into oscillatory motion and each connecting one of said crank devices to one of said

cams to oscillate the same through predetermined phase displaced angles, said followers being so positioned within the angles of movement of respective cams that the periods of actuation thereof by the cams overlap during movement of the cams in one direction of their respective oscillations and follow in succession without overlap during movement of the cams in the other respective directions.

3. In a valve actuating mechanism, a pair of oscillatory cams, a follower for each of said cams, a valve actuating member operable to be effectively actuated by said cams and followers only when both said followers are actuated together by said cams, a driving element adapted to be continuously rotated, a pair of driving eccentrics coupled to said driving element so as to be rotated thereby and displaced in phase with respect to one another, a pair of driven eccentrics each coupled by a link to one of said driving eccentrics so that said driven eccentrics are adapted to be oscillated by said driving eccentrics through angles of movement displaced out of phase with one another, each driven eccentric being coupled to one of said cams to oscillate the same and said followers being so positioned within the paths of movement of the respective cams that the periods of actuation thereof by the cams overlap during movement of the cams in one direction of their respective oscillations and follow in succession without overlap during movement of the cams in the other respective directions.

4. In a valve actuating mechanism as claimed in claim 1, the provision of means operable to displace the followers of the cams in unison around the paths of the respective cams in directions such that the extent of overlap in the actuation of the followers by the cams is not altered.

5. In a valve actuating mechanism as claimed in claim 1, the provision of means operable to displace one of the followers along the path of its cam independently of the other follower to vary the extent of overlap in the actuation of the two followers.

6. In a valve actuating mechanism as claimed in claim 1, the provision of means operable to displace the followers of the cams in unison around the axes of the respective cams in directions such that the extent of overlap in the actuation of the followers by the cams is not altered and means operable to displace one of said followers along the path of its cam independently of the other follower to vary the extent of overlap in the actuation of the two followers.

7. In a compression ignition internal combustion engine comprising at least one cylinder provided with a yieldingly controlled fuel injection valve and at least one air inlet valve and at least one exhaust valve, the combination of an actuating mechanism as claimed in claim 1 adapted to actuate said fuel valve, with a pair of additional cams one being adapted to be oscillated in unison with one of the oscillatory cams to actuate said air inlet valve and the other with the other oscillatory cam to actuate said exhaust valve, the fully open position of each of the said inlet and exhaust valves coinciding with a terminal position in the oscillation of the respective additional cam, and means operable to displace at least one of the followers of the oscillatory cams along the path of movement of its cam.

8. In a valve actuating mechanism, a pair of oscillatory cams, a valve actuating member provided with a pair of surfaces, one associated with each cam and each of which is disposed parallel

to the path of the peak of its associated cam, a roller disposed between each cam and surface to transfer the thrust of the cam to the valve actuating member, said member being operable to be effectively actuated only when both said rollers are actuated together by said cams, a driving element adapted to be continuously rotated, a pair of mechanisms each adapted to convert rotary motion into reciprocatory motion and connected on the one hand in driven relationship to said driving element with a phase displacement with respect to one another and on the other hand each to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams and a carrier member for at least one of said rollers, said carrier being movable to displace its roller about the axis of oscillation of the cam associated therewith and alter the position of the roller along the path of the said cam.

9. In a valve actuating mechanism, a pair of oscillatory cams, a valve actuating member provided with a pair of surfaces, one associated with each cam and each of which is disposed parallel to the path of the peak of its associated cam, a roller disposed between each cam and surface to transfer the thrust of the cam to the valve actuating member, said member being operable to be effectively actuated only when both said rollers are actuated together by said cams, a driving element adapted to be continuously rotated, a pair of mechanisms each adapted to convert rotary motion into reciprocatory motion and connected on the one hand in driven relationship to said driving element with a phase displacement with respect to one another and on the other hand each to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams, a carrier member for each of said rollers, said carriers being movable to displace their rollers about the axes of oscillation of the respective cams and alter the position of the rollers along the paths of the cams, and a coupling device between said carriers to maintain the effective overlap of the cams on said rollers unaltered when one of the carriers is moved.

10. In a valve actuating mechanism, a pair of oscillatory cams, a valve actuating member provided with a pair of surfaces, one associated with each cam and each of which is disposed parallel to the path of the peak of its associated cam, a roller disposed between each cam and surface to transfer the thrust of the cam to the valve actuating member, said member being operable to be effectively actuated only when both said rollers are actuated together by said cams, a

driving element adapted to be continuously rotated, a pair of mechanisms each adapted to convert rotary motion into reciprocatory motion and connected on the one hand in driven relationship to said driving element with a phase displacement with respect to one another and on the other hand each to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams, a carrier for each of said rollers, said carriers being movable to displace said rollers about the axes of oscillation of the respective cams and alter the position of the rollers along the paths of the cams, and a coupling device between said carriers selectively operable to afford relative movement between said carriers to enable one carrier to displace its roller independently of the other and to afford simultaneous movement of both said carriers and rollers to maintain the effective overlap of the cams on the rollers unaltered.

11. In a valve actuating mechanism, a pair of oscillatory cams, a valve actuating member provided with a pair of surfaces, one associated with each cam and each of which is disposed parallel to the path of the peak of its associated cam, a roller disposed between each cam and surface to transfer the thrust of the cam to the valve actuating member, said member being operable to be effectively actuated only when both said rollers are actuated together by said cams, a driving element adapted to be continuously rotated, a pair of mechanisms each adapted to convert rotary motion into reciprocatory motion and connected on the one hand in driven relationship to said driving element with a phase displacement with respect to one another and on the other hand to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams, a cage rotatably mounted about the axis of oscillation of each of said cams, each cage embracing the roller of the cam co-axial with said cage and adapted to move said roller round the axis of said cam, means rotatively coupling said cages together including a pair of gears and means for rotatably moving said gears.

12. In a valve actuating mechanism, a pair of oscillatory cams, a valve actuating member provided with a pair of surfaces, one associated with each cam and each of which is disposed parallel to the path of the peak of its associated cam, a roller disposed between each cam and surface to transfer the thrust of the cam to the valve actuating member, said member being operable to be effectively actuated only when both said rollers are actuated together by said cams, a driving element adapted to be continuously rotated, a pair of mechanisms each adapted to convert rotary

- motion into reciprocatory motion and connected on the one hand in driven relationship to said driving element with a phase displacement with respect to one another and on the other hand to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams, a cage rotatively mounted about the axis of oscillation of each of said cams, each cage embracing the roller of the cam coaxial with said cage and adapted to move said roller about the axis of said cam, means including a pair of helical gears rotatively coupling said cages together, means for rotatively moving said gears and means for moving one helical gear axially with respect to the other.
13. In an internal combustion engine a crank shaft, a fuel injection valve, a pair of oscillatory cams, one associated with each cam and each of which is disposed parallel to the path of the peak of its associated cam, a roller disposed between each cam and surface to transfer the thrust of the cam to the valve actuating member, said member being operable to be effectively actuated only when both said rollers are actuated together by said cams, a driving element adapted to be continuously rotated, a pair of mechanisms each adapted to convert rotary motion into reciprocatory motion and connected on the one hand in driven relationship to said driving element with a phase displacement with respect to one another and on the other hand to one of said cams to oscillate the same through predetermined phase displaced angles determined by the phase displacement of said mechanisms, said rollers being so positioned in the paths of oscillatory movement of the respective cams that the periods of actuation of the rollers by the cams overlap during movement of the cams in one direction of their respective oscillations and follow in succession without overlap during movement of the cams in the other respective directions due to the phase displacement between the cams, a cage rotatively mounted about the axis of oscillation of each of said cams, each cage embracing the roller of the cam coaxial therewith and adapted to move said roller about the axis of said cam, means including a pair of helical gears rotatively coupling said cages, one of said gears being axially displaceable, a lever mechanism operatively connected to said axially displaceable helical gear to effect axial displacement thereof, a displaceable fulcrum device operable to vary the effective leverage of said mechanism and a governor responsive to the speed of said crank shaft of the engine and operatively connected to the displaceable fulcrum device to reduce the said leverage during a predetermined lower speed range of the crank shaft.
14. In an internal combustion engine a crank shaft, a fuel injection valve, a pair of oscillatory cams, a follower for each of said cams, a valve actuating member operable to be effectively actuated by said cams and followers only when both said followers are actuated together by said cams, a driving element adapted to be continuously rotated, a pair of mechanisms each adapted to convert rotary motion into reciprocatory motion and connected on the one hand in driven relationship to said driving element with a phase displacement with respect to one another and on the other hand to one of said cams to oscillate the same through predetermined phase displaced angles determined by the phase displacement of said mechanisms said followers being so positioned in the paths of oscillatory movement of the respective cams that the periods of actuation of the followers by the cams overlap during movement of the cams in one direction of their respective oscillations and follow in succession without overlap during movement of the cams in the other respective directions due to the phase displacement between the cams, a movable carrier operable to displace at least one of said followers along the path of its cam to vary the extent of the effective overlap of the cams, a lever mechanism operable by an operator to actuate said carrier, a device operable to vary the effective leverage of said mechanism and a governor responsive to the speed of said crank shaft and operatively connected to the leverage varying device to reduce the said leverage during a predetermined lower speed range of the crank shaft.
15. In a valve actuating mechanism, the provision of a driving member adapted to be continuously rotated, a pair of mechanisms operable to convert rotary motion into oscillatory motion and operatively connected to said driving member with a phase displacement with respect to one another, a pair of oscillatory cams each operatively connected to one of said pair of mechanisms to be operated thereby through phase displaced angles determined by the phase displacement of said mechanisms, a valve actuating member provided with a pair of surfaces one associated with each cam and each of which is disposed parallel to the path followed by the peak of its associated cam, a follower disposed between each cam and associated surface to transmit the thrust of the cam to the valve actuating member, said actuating member being adapted to be effectively actuated solely when both cams overlap in their action upon said followers, said followers being so located on the paths of movement of the respective cams that the actuation of the followers by said cams at least partly overlap during movement of the cams in one direction of the respective oscillations and follow separately in succession during movement of the cams in the other respective directions, and means operable to adjust at least one of said followers in its position about the axis of oscillation of the cam associated therewith.
16. In a valve actuating mechanism, the provision of a driving member adapted to be continuously rotated, a pair of mechanisms operable to convert rotary motion into oscillatory motion and operatively connected to said driving member with a phase displacement with respect to one another, a pair of oscillatory cams each operatively connected to one of said pair of mechanisms to be operated thereby through phase displaced angles determined by the phase displacement of said mechanisms, a valve actuating member provided with a pair of surfaces one associated with each cam and each of which is disposed parallel to the path followed by the peak of its associated cam, a follower disposed between each cam and associated surface to transmit the thrust of the cam to the valve actuating member, said actuating member being adapted to be effectively actuated solely when both cams overlap in their action upon said followers, said fol-

5 lowers being so located on the paths of movement of the respective cams that the actuation of the followers by said cams at least partly overlap during movement of the cams in one direction of the respective oscillations and follow separately in succession during movement of the cams in the other respective directions and means operable to adjust both said followers in their positions simultaneously about the axes of oscillation of their respective cams in directions such as to maintain the effective overlap of the cams unaltered.

10 15 20 17. In a valve actuating mechanism, the provision of a driving member adapted to be continuously rotated, a pair of mechanisms operable to convert rotary motion into oscillatory motion and operatively connected to said driving member with a phase displacement with respect to one another, a pair of oscillatory cams each operatively connected to one of said pair of mechanisms to be operated thereby through phase displaced angles determined by the phase displacement of said mechanisms, a valve actuating member provided with a pair of surfaces one as-

sociated with each cam and each of which is disposed parallel to the path followed by the peak of its associated cam, a follower disposed between each cam and associated surface to transmit the thrust of the cam to the valve actuating member, said actuating member being adapted to be effectively actuated solely when both cams overlap in their action upon said followers, said followers being so located on the paths of movement of the respective cams that the actuation 10 of the followers by said cams at least partly overlap during movement of the cams in one direction of the respective oscillations and follow separately in succession during movement of the cams in the other respective directions, means 15 operable to adjust at least one of said followers in its position about the axis of oscillation of the cam associated therewith independently of the other follower and means operable to adjust both said followers in their positions simultaneously 20 about the axes of oscillation of their respective cams in directions such as to maintain the effective overlap of the cams unaltered.

STANLEY HERBERT ATTWOOD.
